WEATHER STRIPPING STRUCTURE FOR CAR
WINDOWSJoseph Schunk, Newark, N. J., assignor to The
National Lock Washer Company, Newark, N. J.,
a corporation of New Jersey

Application September 10, 1936, Serial No. 100,100

4 Claims. (Cl. 189—65)

The present invention relates to an improvement in weatherstripping structure for car windows, particularly railway cars, busses, or the like, and has for an object to provide top weatherstripping to produce a seal between the top of the window sash and the top of the window frame which will be effective along the entire length of the sash, whether or not the sash is in its truly aligned position or in a cocked position, that is, a position that makes one corner of the sash higher than the other. Quite often this cocked position is brought about by the fact that the railway car openings vary, so that while some of them are reasonably square others may be considerably out of square. Also the condition may be produced by warping or strain on the parts of the car structure.

It is proposed to provide weatherstripping upon the face of the top rail of the sash for engagement with a vertically disposed angle bar, the engaging surface of the angle bar being relatively wide in a vertical direction, and further to provide means for maintaining the sash in tight relation with the angle bar while at the same time permitting angular variation between them.

With the above and other objects in view an embodiment of the invention is shown in the accompanying drawing and this embodiment will be hereinafter more fully described with reference thereto and the invention will be finally pointed out in the claims.

In the drawing:

Fig. 1 is a side elevation of one corner of the upper portion of the window structure according to the invention, a portion of the header structure being shown in section.

Fig. 2 is a vertical sectional view, taken along the line 2—2 of Fig. 1.

Fig. 3 is a horizontal sectional view, taken along the line 3—3 of Fig. 2.

Fig. 4 is an elevation of the sash removed.

Similar reference characters indicate corresponding parts throughout the several figures of the drawing.

Referring to the drawing in which one end only of the structure is illustrated, the other end being identical, the window structure comprises side posts 10, a top cross bar 11 of L-shape in cross-section, and a sill 12, the side posts being mounted upon the inner frame structure 13 of the car, and the bar 11 being secured by screws 11a to the header structure 14 of the car. The sash comprises a top rail 15, side strips 16, and a glass panel 17, the side strips being slidably mounted for vertical movement in vertically disposed

channel structures 18 mounted upon the side posts 10.

The top rail 15 of the sash is provided in its outer face with a dovetail channel 19 extending the full length of the rail and in which there is engaged a length of weatherstripping 20, which projects beyond the face of the rail and in the normal closed position of the window engages the vertical inner face of the angle bar 11, which inner face is considerably wider in a vertical direction than the strip 20 and extends for a distance above and below it, so that the weatherstripping remains in contact with the bar irrespective of the degree of cocking of the window.

Upon the upper edge of the rail 15 there is secured near each end of the rail an inverted U-shape spring 21, the foot 22 upon the inner leg being secured to the rail by screws 23, and the outer leg being provided at its end with a rounded contact surface 24 which bears upon an angular bearing plate 25 secured to the angle bar 11 by rivets 26, and which bearing plate is of a suitable metal designed to reduce friction, as stainless steel, for example. It will be seen that the spring clips arch over the bar 11 for a sufficient distance to permit of considerable cocking of the window sash, and at the same time the spring pressure of the clip pulls the weatherstripping into snug engagement with the inner face of the bar. The rail is preferably provided with two spring clips, one near each end, although windows of unusual length may be provided with a greater number. It will be noted that the lower edge of the spring ends 24 are above the horizontal plane of the lower edge of the weatherstripping 20 so that when the upper rail of the sash is engaged with the bar 11, in closing the window, the weatherstripping is engaged with the vertical inner surface of the bar 11 before the end 24 engages the outer surface, in other words, before there is any lateral spring pressure exerted upon the weatherstripping. In this way the window may be closed easily, and there will be no tendency for the weatherstripping to be pulled out through frictional engagement with the edge of the upper edge of the bar 11 as the window is closed.

I have illustrated and described a preferred and satisfactory embodiment of the invention, but it will be obvious that changes may be made therein, within the spirit and scope thereof, as defined in the appended claims.

Having thus described my invention what I claim and desire to secure by Letters Patent is:

1. In a window structure, a frame including a top member extending the width of the frame,

a window sash including a top rail member arranged to oppose said top frame member, weatherstripping carried by one of said members and projecting therefrom, the other member having
5 a vertical surface engaged by said weatherstripping and being greater in its vertical dimension than the vertical dimension of said weatherstripping, and spring means carried by said top rail member extending over the top of said top frame
10 member in spaced relation and engaging it only at its side remote from said top rail member to draw said vertical surface and weatherstripping toward each other.

2. In a window structure, a frame including a
15 top member extending the width of the frame and having a vertically disposed surface, a window sash including a top rail member having a vertically disposed surface arranged to oppose said vertical surface of said top frame member, weatherstripping carried by one of said members along its full width and projecting therefrom to engage the opposed vertical surface, said last mentioned vertical surface being greater in its vertical dimension than the vertical dimension of said
20 weatherstripping, and a plurality of longitudinally spaced spring members carried by said top rail member extending over the top of said top frame member in spaced relation and engaging it only at its side remote from said top rail member to draw said vertical surface and weatherstripping toward each other.

3. In a window structure, a frame including a top member extending the width of the frame and having a vertically disposed surface, a window

sash including a top rail member arranged to oppose said vertical surface of said top frame member, weatherstripping carried by said top rail and projecting therefrom to engage the opposed vertical surface, said opposed vertical surface being greater in its vertical dimension than the vertical dimension of said weatherstripping, and spring means carried by said top rail member extending over the top of said top frame member and engaging it only at its side remote from said top rail member to draw said vertical surface and weatherstripping toward each other, the lower edge of said spring means being above the horizontal plane of the lower edge of said weatherstripping.

4. In a window structure, a frame including a top member extending the width of the frame and having a vertically disposed surface, a window sash including a top rail member arranged to oppose said vertical surface on said top frame member, weatherstripping carried by said top rail member along its full width and projecting therefrom to engage the opposed vertical surface, said opposed vertical surface being greater in its vertical dimension than the vertical dimension of said weatherstripping, and a plurality of spaced inverted U-shaped spring members secured to said top rail member arched in spaced relation over said top frame member and engaging it at only its side remote from said top rail member to draw said vertical surface and weatherstripping toward each other.
